THOMAS J. DIXON

BY *Fred G. Dietrich & Co*
ATTORNEYS

UNITED STATES PATENT OFFICE.

THOMAS J. DIXON, OF MADISON, WISCONSIN.

GAME APPARATUS.

Application filed May 31, 1921. Serial No. 473,571.

To all whom it may concern:

Be it known that I, THOMAS J. DIXON, a citizen of the United States, residing at Madison, in the county of Dane and State 5 of Wisconsin, have invented a new and useful Game Apparatus, of which the following is a specification.

My invention has reference to that class of game devices or apparatus in which the 10 use of balls, marbles and the like are projected by being thrown or tossed into receiving compartments of relatively fixed value, and in which means is also included for returning the played projectiles to a receiver 15 adjacent the player so that the operation of playing the game may be conveniently repeated.

Primarily my invention seeks to provide a game of the general character stated, of 20 a relatively simple and economical construction, that will interest grown persons as well as children, that can be conveniently carried from place to place and utilized as a parlor game and in which in addition to the usual 25 element of chance, is required keenness of the eye and accuracy in tossing the projectiles to insure success.

Another object of my invention is to provide in a game apparatus of the character 30 stated, a combined arrangement of a nest of pockets or compartments, having a target-like arrangement; that is, a central or "bull's eye" pocket, the most difficult one 35 into which to cast or toss a projectile, and progressively increasing in size pockets of successively reduced values, and a surrounding receiver for catching wild or canted shots combined with returns, one for each 40 pocket for leading the projectiles (marbles) back to the players' stand where they are received in rack or counter receptacles so 45 that the value of all of the projectiles allowed to the player can be almost instantly read and checked up.

With other objects in view, my invention comprehends a game of the type stated, that can be easily played by any one, young or old, that affords much pleasure and interest to the players and which embodies the peculiar 50 features of construction and novel detailed description, specifically mentioned in

the appended claims and illustrated in the accompanying drawings, in which:—

Figure 1 is a perspective view of my game apparatus shown as set up for use. 55

Figure 2 is a vertical longitudinal section thereof, parts being in side elevation.

Figure 3 is a detail perspective view of the front or collecting rack into which the played marbles are gathered. 60

Figure 4 is a vertical section of one of the collecting racks in which the return marbles gather.

Figure 5 is a horizontal section taken substantially on the line 5—5 of Figure 2. 65

Briefly stated, my game comprehends the use of projectiles (preferably marbles) which are tossed from a prescribed distance to a nest of practically annularly disposed vertical pockets, the central one of which 70 has a relatively high or bull's eye value; those marbles that pass into any of the pockets counting as hits, while those that strike the upper edges of the pocket and are reflected laterally are caught in a main 75 receiver are misses, means in the nature of a series of individual returning tubes, one from each of the pockets and the main receiver being included and which terminate in vertical racks having the designations 80 corresponding to the value of their respectively connected pockets.

In the practical development of my game apparatus, the same is constructed of any suitable material, preferably thin sheet 85 metal finished by painting or enamelling. The body portion of the apparatus comprises a series or nest of vertical pockets and these are preferably of longitudinally elongated shape so that the said nest of 90 pockets are compactly assembled and the marbles tossed to the said nest of pockets, that miss the pockets and engage the rims thereof are prevented from bounding away too far and for being readily caught into a 95 main hopper-like receiver that surrounds the entire nest of pockets in the manner clearly shown in the drawings.

The pockets, of which there may be any suitable number, five being shown, are designated 1, 2, 3, 4 and 5, beginning with the center or bull's eye which has the smallest

area, is the most difficult one in which to toss the marbles and which counts the most, it having the highest value. It is to be understood that when two or more play the game, the winner is the one that gathers the greatest number of shots in the high value pockets, and readable at the rack-like counters or receivers of the return troughs 0, 1, 2, 3, 4 and 5.

10 As best shown in Figure 2, the nest of pockets is disposed on a slight vertical incline, and a single flat member 7 constitutes the bottom for all of the pockets. By reason of inclining the pockets, as stated and 15 shown, all projectiles (marbles) that are received therein and drop to the bottom thereof, roll toward the lower front end.

Each of the pockets or compartments 1-5 has an outlet 8, at the lower or front end, 20 into which the marbles pass and through which they discharge into a short pendent tube 80 (one for each pocket), the lower end of which terminates in a forwardly projected horizontal portion 81, as is best shown 25 in the aforesaid Figure 1, by reference to which it will be noticed the several marble outlet tubes 81 are concentrated and have their ends positioned for being telescopically engaged by a series of return tubes 82 30 which extend some distance from the nest of pockets to a point adjacent where the player is supposed to stand, when playing the game.

The forward ends of the several tubes 82 35 terminate in pendent portions 83, open at the bottom, and provided with vertically elongated sight slots 84 through which the number of marbles gathered therein may be readily counted.

40 The pendent tube portions 83 serve as counting racks and each has its open bottom normally covered by a spring closed cap plate 85, the tension of the spring 85' being sufficient to hold the plate 85 to the closed 45 position against the weight of any number of the marbles that may collect in the counting rack or tube 83, the closure plate 85 being equipped with a tripper finger 86, whereby the said cap plates may be readily 50 swung down, see dotted position in Figure 4, to permit releasing all of the marbles collected in the counter tube and for being conveniently gathered by the player.

To indicate the values of the several tube 55 portions 83, in which the marbles, that count as shots, are collected, the upper bent portions of such tubes are flattened as at 87 to provide designating number receiving surfaces, the several racks or tubes having 60 the numbers arranged as is clearly shown in Figure 3, which also indicates a supplemental tubular rack designated "0" into which the missed shots (marbles) are collected and which pass from a supplemental hopper

like pocket 88 that extends entirely around 65 the nest of pockets 1-5.

The supplemental or hopper-like pocket 88, in practice, is of such size and surrounds the nests of pockets 1-5 in relatively such manner, that all of the marbles, as they are 70 tossed to the nests of pockets and which miss such pockets, that is, strike against the upper edges thereof and are laterally canted, are caught therein.

The supplemental pocket 88 may be 75 formed of some stiff material that will hold its shape but it is preferably made of cloth formed into an inverted hood shape, the soft body serving to deaden the noise of the marbles that contact or strike against said 80 body.

When made of cloth, as indicated in the drawing, the body 88 is held stiff or taut by a series of rigid ribs 89 on the inside thereof, which ribs are joined at their upper 85 and lower ends by draw strings 9-90, the ribs and the body being arranged somewhat like an umbrella body, so the said body 88, when removed from the nests of boxes, can be folded up like an umbrella. 90

The lower end of the body 88 is of a diameter to snugly slip over the outside of the lower end of the outer one 5, of the nests of pockets, and to provide for rigidly sustaining the said body 88 to its hopper-like 95 shape it has attached guy strings 10-10 connected to the upper ends of the ribs 9, and whose free ends are adapted for being connected to fastening eyes 11 along the lower edge of the outer pocket 5, as shown. 100

While I have not so illustrated it, it is obvious the hopper-like body 88 may be made of wire screening or other like material, and when thus formed, the ribs and guy strings will not be necessary, but for 105 reasons above mentioned, I prefer to make the body 88 of cloth with means equipped for holding it in its practically rigid or extended condition onto the nest of pockets as stated. 110

The bottom of the large receiver 88 has an outlet 88^a for the escape of the missed shots, the caught marbles passing through a tube 88^b to a supplemental pendent tube portion 83^a formed like the other rack or counting tubes 83, the same being designated "0" in the drawing, which shows the tube 83^a as also equipped with a spring closed cap 85 that normally covers the lower end thereof to collect the missed shots. 115 120

Due to the small size of the combined parts that constitute my apparatus this game can be readily moved from one home to another. The projectiles used in the game are only as large as a small marble, 125 hence no physical exercise is required to play, since the game is for amusement purposes only.

The counting racks or tubes 83—83^a being at the players' stand, the game can be repeated as often as desired, since the marbles are all returned to the player in condition for being conveniently gathered by such player.

The several racks or counting tubes may also be made of wire screening, through which the marbles may be seen, but I prefer to make the said members of solid tubing with long sight slots, as shown, which makes it easy to add up the total counters in each collecting tube or rack.

From the foregoing description, taken in connection with the accompanying drawing, the complete construction, the manner in which the game is played, and its advantages will be readily apparent to almost any one.

20 The marbles are tossed (not thrown) in the same manner as tossing a coin from one person to another. The parts are so combined and arranged that they may be readily shaped up from sheet metal in an easy and very inexpensive manner.

25 The nest of pockets being of oval shape, that is, in the direction of the length of the apparatus, instead of circular, provides a more compact arrangement of the parts and 30 renders it more difficult to make the shots than would be the case were the receiving pockets circular.

To add interest to the game, the "bull's eye" or center pocket has a gong 15, suitably located within the pocket, to be struck by the marble caught therein, as it drops to the bottom for indicating to the player that a "bull's eye shot" was made.

35 To make difficult the tossing of the marbles in the central or "bull's eye" pocket as they are tossed toward the center of the nest of the pockets, the series of pockets that surround the central pocket 1 are of gradually decreasing depth toward their front end 45 and of corresponding increasing depth from the central pocket to their farthest end, as is best shown in Figure 1.

The gradually increasing depth of the pockets 2, 3 and 4, from the front to the back end thereof, makes the placing of the marbles into the lesser value pockets relatively easy and practically overcomes the danger of the projectiles (marbles) passing beyond the nest of pockets.

50 In playing the game, each player, in his or her turn, pitches preferably five marbles, one at a time, at the bull's eye or target portion 5. In pitching the marbles or balls, if one ball goes in pocket 2, this counts 2 55 points; if one goes in pocket 4 it counts 4 points and if one goes in the bull's eye 5 it counts 5 points and if the other two go into the hopper "0" they count nothing, thus making a total of eleven points. The

winner is the one who makes preferably 100 65 points first.

It is obvious that in the practical development of my game apparatus, the exact details shown may be modified or varied to suit the size of which the apparatus may 70 be built. For the larger sizes, in which the projectiles are of a relatively heavy or large diameter, the connections with return tubes 82 may be in the nature of open troughs or runways from their receiving 75 ends to near their outer ends where they connect with the pendent racks 83.

What I claim is:

1. In a game apparatus of the character described, a series of vertically disposed receptacles, each of the said receptacles being of relatively progressively increasing depth, each individual receptacle increasing in height from the front to the rearmost ends, a flexible annular receiver that surrounds the 85 nest of receptacles, the said receiver being adapted for catching the projectiles that are not caught within the vertical receptacles, the said receiver increasing in depth from the front to the rear end, the said receiver 90 being removably attached to the receptacle's body, and means for sustaining the flexible receiver body in rigid relation with respect to the receptacles and when operatively applied, the said receiver and the receptacle 95 each having an outlet for the passage therethrough of the projectile caught therein.

2. In a game of the character described, a receptacle into which a marble may be tossed by a player standing some distance from the 100 said receptacle, a receiver that surrounds the receptacle for catching the missed shots or projectiles that engage the outer edge of the receptacle and are laterally deflected therefrom, a separate return tube connected with 105 each of the receptacles and with the receiver and a pendent collecting pocket connected to the outer end of each of the return tubes, said collecting pockets each having a vertical slotway in line therewith for visual observation of the marbles collected therein and each having a normally spring-held closure cap provided with a finger trip whereby by tripping the closure cap the player can gather in the hand, the marbles contained in 115 the said collecting pockets.

3. In a game of the character described, a nest of receptacles of progressively increasing depth from the smallest or innermost one of the nest, the several receptacles being of 120 elongated shape in the direction of the length of the apparatus, whereby a series of continuous annularly disposed spaces are formed into which marbles may be tossed by a player standing some distance away from 125 the receptacles, an outer trough shaped receiver that surrounds the nest of receptacles, each of the receptacles and the receiver hav-

ing an outlet for the marbles caught therein, means for separably collecting the marbles from the different receptacles and the receiver, the said means being located some 5 distance in advance of the receptacles and the receiver, and returns individually connecting the several receptacles and the receiver with the marble collecting means.

4. In a game of the character stated, a series of annularly disposed pockets each of 10 the said pockets being relatively of progressively increasing depth, each individual pocket increasing in height from the front to the rearmost ends, a receiver that surrounds 15 the nest of pockets and is adapted for catching the projectiles that are not caught in the nest of pockets, the said receiver and each of the pockets having an outlet for the free passage therethrough of the projectiles caught 20 therein and a series of separate ball collecting pockets, one for each of the nest of pockets and the receiver and a runway connecting each of the outlets with their respective ball collecting pockets.

25 5. A game apparatus of the character described, comprising a suitable supporting

frame, a series of annularly disposed vertical receptacles, the said receptacles being of progressively increasing depth, a flat member that constitutes a bottom for all of the 30 said receptacles, an annular receiver of gradually increasing depth from its front to its rear end, the said receiver surrounding the series of annular receptacles adapted for catching such of the projectiles tossed toward and not caught in the receptacles, a series of separate projectile collecting pockets located some distance forward of the caught 35 elements and adjacent the stand for the player, one of the said pockets being provided for each of the series of receptacles and the receiver, the said pockets each having a shiftable closure cap that constitutes the bottoms of the said pockets, a runway connecting each of the series of pockets and 40 the receiver with their respective projectile catching receptacles and the receiver with the aforesaid flat bottom member having openings for the passage of the projectiles thereto into their respective runway.

THOMAS J. DIXON.
